F. G. Fischer

ATTORNEY.

UNITED STATES PATENT OFFICE.

SAMUEL J. MATHEWS, OF KANSAS CITY, MISSOURI, ASSIGNOR TO B & B MANUFACTURING AND DRILLING COMPANY, A CORPORATION OF DELAWARE.

DRILLING-GEAR.

1,300,988.

Specification of Letters Patent. Patented Apr. 15, 1919.

Application filed October 10, 1917. Serial No. 195,737.

To all whom it may concern:

Be it known that I, SAMUEL J. MATHEWS, a citizen of the United States, residing at Kansas City, in the county of Jackson and 5 State of Missouri, have invented certain new and useful Improvements in Drilling-Gears, of which the following is a specification.

My invention relates to improvements in 10 well drilling gear, and my object is to provide simple but efficient means to retain a fluid in the gear housing and prevent the entrance of water to the motors arranged within said housing for the purpose of driving 15 the drilling tool and its shaft.

In order that the invention may be fully understood, reference will now be made to the accompanying drawing, in which:

Figure 1 is a vertical section of a well 20 with my gear in position therein.

Fig. 2 is an enlarged, broken section on line II—II of Fig. 1.

Fig. 3 is an enlarged, broken section on line III—III of Fig. 1.

Fig. 4 is an enlarged, broken section on 25 line IV—IV of Fig. 1.

In carrying out the invention, I provide a suitable housing consisting, preferably, of a plurality of sections 1, 2, 3, 4, 5, 6, 7 and 30 8 connected by nipples 10, so that access may be had to any of the bearings 12, in which the tool drive shaft 14 is journaled. Said shaft 14 is driven by electric motors 16, any number of which may be employed.

The lower portion of the section 3, has a 35 transverse partition 17, provided with an opening 18 through which lubricating oil, insulating oil, or a combination of both may be introduced. Normally the opening 18 is 40 closed by an air-tight plug 20, to relieve the top of the column of oil of atmospheric pressure.

In order that all of the sections from the 45 partition 17 to the section 8, inclusive, may be filled with oil, ports 22 are formed in the bearings 12, so that as the oil is introduced through the opening 18, it will flow through the ports 22 until all of said sections are 50 filled to the partition 17.

The oil is prevented from escaping through the lowermost bearing 12 by packing 25 and a gland 26.

Traps 27 and 28 are applied to that portion of the shaft 14 extending through the

sections 7 and 8. Each trap comprises a 55 container 30, fixed to the shaft, and a baffle or sleeve 31 depending from the adjacent bearing 12, as disclosed by Fig. 4.

When introducing the oil into the sections through the opening 18, the air in the latter 60 is displaced by said oil. Hence there will be atmospheric pressure exerted on the oil to retain it in the sections when the plug 20 is closed. However, the packing 25 in the lowermost bearing 12 soon becomes worn 65 sufficiently to admit air into the section 8, but since this air is at atmospheric pressure it tends to prevent the oil from leaving the lowermost container 30.

Should water enter the section 8 through 70 the worn packing, it will flow into the lowermost container 30 until it reaches the lower end of the baffle 31, where it remains, owing to its specific gravity being greater than that of the oil. Sealing of the oil within the 75 sections insures lubrication for all of the bearings 12 and the shaft 14, and obviates all danger of damage to the motors from water, as the latter is effectually excluded 80 from the sections or chambers containing said motors.

In practice, the trap 27 is found efficient in retaining the oil and excluding water, but as a precautionary measure I also employ 85 the second trap 28.

The uppermost section 1 is supported by a swivel member 35, which is connected to a cable (not shown), employed in raising and lowering the housing, and in order that said swivel 35 may be constantly lubricated where 90 it extends through the upper portion of the section 1, and water excluded from the section, I provide said section with a trap 36 embodying a container 37, fixed to the swivel 35, and a baffle 38, threaded into the section 1. Should water in the well reach a level 95 with the top of the trap 36, it will pass upwardly therein to the top of the baffle 38 and thus seal the oil, which is lighter than the water, between the top of said baffle and the adjacent wall of the container 37.

From the foregoing description, it is apparent that I have produced efficient means for lubricating the tool shaft 14 and its bearings, and also for excluding water from the motors 16, and while I have shown and described the preferred form of my invention, I do not exclude such changes in the 105

construction, proportion, and arrangement of parts as properly fall within the spirit and scope of the claims.

Having thus described my invention, what I claim and desire to secure by Letters Patent, is:

1. In a drilling gear of the character described, a housing containing a lubricant, and means secured to the drilling gear to retain said lubricant in said housing.
2. In a drilling gear of the character described, a housing containing a lubricant, and a container secured to the drilling gear to retain the lubricant in said housing.
3. In a drilling gear of the character described, the combination of a suitable cutting means, a motor for driving said cutting means, a housing in which said motor is mounted, a column of lubricant in said housing, and means coating with atmospheric pressure to retain the column of lubricant in the housing.
4. In a drilling gear of the character described, the combination of a suitable cutting tool, a motor for driving said cutting tool, a housing in which said motor is mounted, a column of lubricant in said housing, and a container at the lower portion of the housing to retain said lubricant in said housing.
5. In a drilling gear of the character described, a housing containing a fluid, and a container secured to the drilling gear to retain the fluid in said housing.
6. In a drilling gear of the character described, the combination of a cutting tool, a suitably driven shaft for actuating said tool, a housing in which said shaft is journaled, a column of liquid in said housing, and a trap surrounding the shaft and arranged in the housing to retain the liquid therein.
7. In a drilling gear of the character described, the combination of a cutting tool, a suitably driven shaft for actuating said tool, a housing in which said shaft is journaled, a column of liquid in said housing, a tubular member within the housing and surrounding a portion of the shaft, and a container surrounding said tubular member and fixed to the shaft.
8. In apparatus of the class described, the combination of an inclosed chamber containing a fluid, a vertical shaft extending through a wall of said chamber, and means for retaining the fluid in the chamber, said means comprising a cup-shaped member outside the chamber and embracing the shaft.
9. In apparatus of the class described, the combination of an inclosed chamber containing a fluid, a vertical shaft extending through a wall of said chamber, a sleeve attached to the chamber and surrounding the shaft, and means for retaining the fluid in the chamber, said means comprising a cup-shaped member outside the chamber and embracing the shaft and the end of the sleeve.
10. In apparatus of the class described, the combination of an air tight chamber containing a fluid, a vertical shaft extending through a wall of said chamber, a sleeve attached to the chamber and surrounding the shaft, and means for retaining the fluid in the chamber, said means comprising a cup-shaped member outside the chamber and embracing the shaft and the end of the sleeve.

In testimony whereof I affix my signature, in the presence of two witnesses.

SAMUEL J. MATHEWS.
